UNITED STATES PATENT OFFICE.

GIUSEPPE ROCCO, OF TRIESTE, AUSTRIA-HUNGARY.

ACETYLENE-GENERATOR.

No. 892,893.

Specification of Letters Patent.

Patented July 7, 1908.

Application filed March 23, 1907. Serial No. 364,172.

To all whom it may concern:

Be it known that I, GIUSEPPE Rocco, a subject of the Emperor of Austria-Hungary, residing at Trieste, Empire of Austria-Hungary, have invented certain new and useful Improvements in Acetylene-Generators; and I do hereby declare the following to be a full, clear, and exact description of the invention, such as will enable others skilled in the art to which it appertains to make and use the same.

My invention relates to acetylene lighting apparatus and more particularly to intermittent light apparatus for sea lights.

In the apparatus constructed in accordance with my invention calcium carbid is automatically introduced in predetermined quantities into water whenever the quantity of acetylene in the gasholder is reduced to a predetermined minimum. The gas flows from the gasholder through a wet gas meter into two tubes, one of which is provided with an adjustable throttling device and the other with a valve or equivalent device opening and closing alternately at and for predetermined intervals, the two tubes lead to a pipe supplying the burners of the intermittent sea light. The throttling device in one of the tubes permits to flow to the burners a quantity of gas which is just sufficient to keep burning small flames which are not visible at a greater distance, whereas the valve or equivalent closing device in the other tube, when open, permits so large a quantity of gas to flow to the burners that the flames are greatly increased and therefore the light becomes very intense and visible at great distances. In this way an intermittent light is obtained. The closing device is alternately opened and shut by a mechanism the movement of which is governed by a pendulum and which is driven by the wet gas meter.

In the accompanying drawings, Figure 1 shows diagrammatically the arrangement of the apparatus as a whole. Fig. 2 is a vertical section of the apparatus for intermittently introducing calcium carbid into the acetylene generator. Fig. 3 is a view similar to Fig. 2 showing the parts in another position, and Fig. 4 shows a detail of the carbid introducing apparatus in elevation. Figs. 2 to 4 are shown on a larger scale than Fig. 1.

1 is an acetylene generator and 2 is a pipe leading from the gas space thereof into the bottom portion of the gas holder 3. The

upper end of the pipe 2 which slightly projects above the water level in the gas holder is covered by a cap 4, the lower edge of which is below the water level so that gas can escape from the pipe into the gas holder but no gas can flow back from the gas holder to the gas generator.

5 is a pipe permitting the gas to flow from the bell of the gas holder to a gas chamber 6 below such bell. 7 is a pipe leading the gas from such chamber to a purifier 8 from which the gas flows through a pipe 9 to a wet gas meter 10 of any known or suitable construction.

11 and 12 are two pipes through which the gas flows from the gas meter to a pipe 13 leading directly to the burners 14. A cord or chain 15 is attached with one end to the upper part of the bell of the gas holder and runs round a loose guide pulley 16 journaled in the gas holder framing. The other end of this cord or chain is attached to a weighted lever 17 pivoted on the gas generator 1 and actuating the mechanism for intermittently introducing calcium carbid into the gas generator.

When the gas holder bell has sunk beyond a predetermined limit the lever 17 is raised by the cord or chain 15 and causes a fresh charge of carbid to be introduced into the generator. The gas then evolved flows to the gas holder raising the bell of the latter; the lever 17 is lowered being weighted and the carbid feeding mechanism of the gas generator is returned into its initial position. When owing to an abundant production of gas the gas holder bell is raised beyond a predetermined limit it opens an escape device, for instance a cock 20 in a pipe 21 communicating with the gas chamber 6, whereupon the excess of gas escapes into the atmosphere. As shown in Fig. 1 the mechanism for operating the escape device or cock 20 consists of a length of rack 18 secured to the gas holder bell and adapted to engage into a toothed segment 19 attached to the cock 20 whenever the bell rises beyond a predetermined point.

The mechanism for intermittently introducing calcium carbid into the water in the gas generator 1 is shown in Figs. 2 to 4. It consists of a slide 22 working in a casing 23 fixed air tight to the neck 24 of the gas generator. For better guiding the slide 22 in the casing a loose roller 25 is journaled in a frame 26 mounted in the slide 22 and springs 27 are interposed between the back wall of

the slide and the frame carrying the roller 25 whereby the roller is held in contact with the front wall of the casing 23.

The slide is hollow and its front wall is provided with an opening which when the slide is in its uppermost position shown in Fig. 2 is just in front of the open end of a carbid funnel 28 leading into the casing 23. In this position therefore the slide is automatically filled 10 with carbid from the hopper. The slide is brought into this uppermost position by a rod 29 connecting the same with the lever 17 whenever the gas holder bell has been raised by gas flowing from the generator into the 15 gas holder and consequently the lever 17 has been turned one way. The lower end of the slide is provided with a pivoted gate or valve 30 having lateral lugs 31 engaging into vertical slots 32 in the casing and with a spring 33 20 tending to open the said gate or valve. In the uppermost position of the slide the gate or valve is prevented from opening by the said lugs 31 engaging the upper straight portions of the slots 32. When, however, owing 25 to the consumption of gas the gas holder bell sinks below a predetermined limit and consequently the outer end of the lever 17 connected to the cord or chain 15 is raised and thereby the rod 29 is lowered and the slide 22 is 30 brought into the position shown in Fig. 3, the upper full portion 34 of the slide 22 comes opposite the open end of the funnel 28 thus stopping the flow of carbid from the said funnel to the interior of the slide. At the 35 same time the lugs 31 come into the enlarged or curved portion 35 of the slots 32 thereby permitting the gate or valve 30 to be opened by the combined action of the carbid within the slide and of the spring 33. The carbid 40 is then discharged into the water contained in the generator and acetylene is evolved and flows to the gas holder. The gas holder bell is raised, the lever 17 being weighted raises the slide 22 into the position shown in Fig. 2 45 and the lugs 31 slide along the curved left hand edge 35 of the slots 32 whereby the gate or valve 30 is closed against the action of the spring 33. The slide is then again charged with carbid as above described and is ready 50 for the next discharge.

If it is desired to altogether stop the production of gas it is only necessary to lock the rod 29 in its uppermost position by a suitable dog 36 as shown in Fig. 1, the said dog 36 55 being pivoted on a vertical axis in the frame of the apparatus and adapted to engage below a shoulder on the rod 29.

In order that the gate or valve 30 may be tightly held to the rear wall of the slide when 60 the latter is in its uppermost position weighted arms 36' may be provided which are pivoted to the casing 23 and which in the uppermost position of the slide bears against the lugs 31 thereby holding them against the 65 rear wall of the slide.

As already described the gas passes from the gas holder through the purifier 8 and pipe 9 and gas meter 10 to two tubes 11, 12, both of which lead to the tube 13 going to the burners 14. One of these tubes 11 contains a 70 throttling device indicated at 11' and of any known or preferred construction which permits only so small a quantity of gas to pass through the tube 11 as is sufficient for keeping burning small flames that are not visible 75 at larger distances. The other tube 12 contains an alternately opening and shutting organ such as a valve, which when open permits to pass through the tube 12 a quantity of gas sufficient for maintaining large flames 80 visible at great distances.

By properly adjusting the intervals between the opening and shutting periods of the said closing organ and by properly adjusting the duration of the opening and shutting periods themselves an intermittent light 85 of any desired character may be obtained.

Claims

1. In acetylene lighting apparatus the combination of an acetylene generator a casing 90 fixed to such generator, a carbid funnel, a port leading from such carbid funnel to the said casing, a hollow slide adapted to reciprocate in such casing, a gas holder having a reciprocating bell, means operated by such 95 bell and adapted to operate the said slide, an opening in the side of the slide, such opening being adapted to coincide with the said port in one extreme position of the slide, an opening at the bottom of the slide, a cover adapted to close such opening in the bottom of the slide, a spring secured to the slide and adapted to open the cover, curved slots in the said casing and lateral lugs on said cover adapted to engage into such slots, substantially as 100 and for the purpose described.

2. In acetylene lighting apparatus the combination of an acetylene generator, a casing fixed to such generator, a carbid funnel, a port leading from such carbid funnel to the 110 said casing, a hollow slide adapted to reciprocate in such casing, a gas holder having a reciprocating bell, means operated by such bell and adapted to operate the said slide, an opening in the side of the slide, such opening 115 being adapted to coincide with the said port in one extreme position of the slide, an opening at the bottom of the slide, a cover adapted to close such opening in the bottom of the slide, a spring secured to the 120 slide and adapted to open the cover, curved slots in the said casing, lateral lugs on said cover adapted to engage into such slots and weighted arms pivoted to said casing and adapted to engage the said lugs on the 125 cover in the said extreme position, of the slide, substantially as and for the purpose described.

3. In acetylene lighting apparatus the combination of an acetylene generator, a casing 130

fixed to such generator, a carbid funnel, a port leading from such carbid funnel to the said casing, a hollow slide adapted to reciprocate in such casing, a gas holder having a reciprocating bell, means operated by such bell and adapted to operate the said slide, an opening in the side of the slide, such opening being adapted to coincide with the said port in one extreme position of the slide, an opening at the bottom of the slide, a cover adapted to, close such cover in the said ex- | treme position of the slide and means for opening such cover in the other extreme position of the slide and means for locking the said slide in position in the said casing, sub- 15 substantially as and for the purpose described.

In testimony whereof, I affix my signature, in presence of two witnesses.

GIUSEPPE ROCCO.
